UNITED STATES PATENT OFFICE.

AUGUSTUS H. BUTTLES, OF MILWAUKEE, WISCONSIN.

SHOE CONSTRUCTION.

1,115,651.

Specification of Letters Patent.

Patented Nov. 3, 1914.

Application filed January 17, 1914. Serial No. 812,618.

To all whom it may concern:

Be it known that I, AUGUSTUS H. BUTTLES, a citizen of the United States, and resident of Milwaukee, in the county of Milwaukee and State of Wisconsin, have invented new and useful Improvements in Shoe Construction, of which the following is a description, reference being had to the accompanying drawings, which are a part of this specification.

This invention relates to improvements in shoe construction.

In the manufacture of shoes it is of great advantage to provide a one piece vamp, but as now ordinarily formed the one piece vamps in connection with the other parts of the uppers do not cut to advantage with relation to the hide and consequently there is considerable waste, and it is impossible to 20 cut as many uppers from the hide as desired.

It is one of the objects of the present invention to overcome the before mentioned objectionable feature and provide a one piece 25 vamp shoe construction which will form a shoe of ornate appearance and which will provide for cutting a greater number of uppers from a hide than is now ordinarily cut.

A further object of the invention is to 30 provide a shoe construction in which the vamp is connected to the quarters in such a manner as to reinforce the instep portion of the shoe.

A further object of the invention is to 35 provide a shoe construction in which the upper portion of the shoe is formed of parts integral with the vamp and quarters.

A further object of the invention is to 40 provide a shoe construction in which the parts when attached together form a shoe well adapted to withstand hard wear and usage.

With the above and other objects in view, the invention consists of the improved shoe 45 construction and its parts and combinations as set forth in the claims, and all equivalents thereof.

In the accompanying drawing in which the same reference characters indicate the 50 same parts in all of the views: Figure 1 is a side view of the improved shoe, a part being broken away to show the construction in the rear thereof; Fig. 2 is a top view of the separate parts of the material forming 55 the shoe upper; Fig. 3 is a rear view of the shoe, a part being broken away to show the

construction in the rear thereof; and Fig. 4 is a rear view of a modified form of shoe.

Referring to the drawing the numeral 8 indicates the vamp, 9 the quarters, 10 the cap, 11 the sole and 12 the heel of the improved shoe construction. The vamp 8 is formed in one piece and is preferably formed separate from the toe piece 13 which is covered by the cap 10 in the completed shoe. 60 The vamp is of angular form and its rear angular edges 14 are adapted to abut against the forward edges 15 of the quarters and is sewed thereto and the seams are then overlapped by the reinforcing instep strips 16 65 which are sewed to the vamp and the quarters on both sides of the seams. These strips extend from the sole 11 of the shoe upwardly and forwardly at an angle over the instep portion of the shoe and terminate at 70 the medial split portion 17 of the vamp which forms the lower laced open part 19 of the shoe and thus serve to cover and reinforce the seam and to also reinforce the instep portion of the shoe where the shoe receives the maximum strain. The upper portions 20 of the vamp on opposite sides of the medial split part form in part the shoe upper, which, when connected to the upper portions 21 of the quarters form the complete shoe upper. The upper forward edge 75 portions of the shoe upper are provided with eyelets 22 and hooks 23 for lacing the opposite edge portions together.

The rear or heel edges 24 of the quarters 80 are positioned in abutting relation and are sewed together and a back stay strip 25 extending vertically from the heel to the upper edge of the shoe upper covers this back seam and is sewed to the abutting edge portions 95 of the uppers and reinforces the same.

The cap 10 which overlaps the abutting edges of the toe piece and the vamp is sewed to the vamp in the usual manner. The sole and heel are also connected to the upper portion of the shoe in the usual manner and a tongue (not shown) is provided for the laced portion.

In the modified form shown in Fig. 4 the two quarters are formed in one piece and consequently the back stay strap 25 is omitted in this form.

While the toe piece is shown as separate from the vamp piece it is to be understood that the toe piece may be formed integral 110 with the vamp without departing from the spirit and scope of the invention.

From the foregoing description it will be seen that the shoe is of simple construction, is inexpensive to manufacture and is well adapted for the purpose described.

5. What I claim as my invention is:

1. In a shoe construction, a one piece vamp shaped to extend to the instep portion of the shoe and forming in part the shoe upper, quarter pieces having their forward edges abutting against the rear edges of the vamp and forming the other portion of the shoe upper, and reinforcing instep strips covering the seams formed by the abutting edges and stitched to the vamp and the quarters.

2. In a shoe construction, a one piece vamp shaped to extend to the instep portion of the shoe and having a medial split portion, quarters having their forward edges abutting against and connected to the rear edges of the vamp, and reinforcing instep strips covering the abutting edges and stitched to the quarters and to the vamp.

3. In a shoe construction, a one piece vamp shaped to extend to the instep portion of the shoe and having a medial split portion, quarters having their forward edges abutting against and connected to the rear instep edge portions of the vamp, the seams formed by said connections extending upwardly and forwardly at an angle from the lower portion of the vamp, and reinforcing instep strips covering said seams.

4. In a shoe construction, a one piece vamp shaped to extend to the instep portion of the shoe and having a medial split por-

tion, quarters joined together at their rear edges and having their front edges abutting against and connected to the rear instep edge portions of the vamp, the seams formed by the abutting edges extending upwardly and forwardly at an angle from the lower portion of the vamp, and reinforcing instep strips covering the seams and stitched to the vamp and to the quarters.

5. In a shoe construction, a one piece vamp shaped to extend to the instep portion of the shoe and having a medial split portion, quarters joined together at their rear edges and having their front edges abutting against and sewed to the rear edges of the instep portions of the vamp, the medial split portion of the vamp and the forward upper edge portions of the quarters being provided with lace holding means, the seams formed by the rear edges of the vamp and the forward edges of the quarters extending upwardly and forwardly at an angle from the lower portions of the vamp and quarters to medial portions of the lace holding means, and reinforcing instep strips covering the seams and stitched to the vamp and to the quarters and extending from the lower portions of the vamp and quarters to the upper edges of the vamp and the upper forward edges of the quarters.

In testimony whereof, I affix my signature, in presence of two witnesses.

AUGUSTUS H. BUTTLES.
